UNITED STATES PATENT OFFICE

2,570,004

SPRAY GUN FOR PROJECTING POWDERED MATERIALS

Rufus S. Penny, Richmond, Va.

Application December 16, 1949, Serial No. 133,281

2 Claims. (Cl. 91—44)

1

This invention relates to spray guns and, more particularly, to a device for injecting powdered materials into the burning contents of a furnace.

The primary object of this invention is to provide a spray gun for injecting chemicals, such as powders for preventing clinkers, into a furnace. In common with other spray or injecting apparatus, the present injection device is adapted to be supplied from a suitable source of compressed air for blasting chemicals fed from a hopper through a hollow spike. When the spike is inserted into the substance to be treated, the chemical will be pneumatically drawn from the hopper and injected into the material surrounding the end of the spike. Heretofore, most such devices have been arranged for injecting chemicals downwardly, as around the roots of a tree. The subject device is intended for substantially horizontal operation so that it can be inserted laterally through a furnace door and into a bed of burning coal.

More particularly, the object of this invention is to provide a hollow spike-type injector having a hopper into which chemicals may be maintained while the spike is rotated about its longitudinal axis. By this arrangement the chemical may be injected upwardly, downwardly, and sideways into the coal bed without spilling of the supply from the hopper. Another object is to provide, at the operator's end of the hollow spike, a rotatable joint which also constitutes a handhold for rotating the spike. Still another object is to provide, near the pointed end of the spike, an outlet opening of gradual, smooth termination so that neither the chemical being dispensed nor the coals being treated will deposit therein.

Other objects are the provision of a hollow spike-type injector operating primarily by pneumatic action but arranged also for gravity and mechanical assistance in the passage of the chemical from the hopper to the air stream.

These and other objects will be apparent from the following specification and drawing in which the sole figure is a side elevation, broken away in parts to illustrate the interior mechanism.

Referring now to the drawing in which like reference numerals denote similar elements, the spray gun indicated generally at 2 is comprised of an elongated hollow spike 4 of sufficient length for extension into a furnace, a throat section 6 in which pneumatic dispatch is effected, a hopper 8 preferably of a size to accommodate sufficient chemical powder for treating a furnace, and an air fitting 10 adapted for connection via a suitable flexible hose (not shown) to a source of compressed air.

2

Hopper 8 includes a funnel-like container 12 welded at its lower end to a spout tube 14 externally threaded at its lower end for screwing engagement into the internally threaded stem of 5 a T fitting 18. In the left-hand branch of T fitting 18 there are a pair of internally-externally threaded reducing thimbles 20, 22 into the interior of which is readily engaged in the end of a short stem pipe 24 which, in turn, is threadably engaged with a manually-controlling off-on valve 26. On the inlet side of the valve there is threadably engaged a nipple 28 about which the flexible compressed air hose (not shown) is fitted.

Also threadably supported in reducing thimble 15 22 is an elongate air blast pipe 30 extending through the interior of T fitting 18 and well into the interior of a casing tube 32 threadably engaged in and extending from the right-hand arm of T fitting 18. It is apparent that when hopper 8 is filled with a chemical powder, some of the powder will be gravity fed immediately into the T fitting section 18 of throat 6 so as to be immediately available for pneumatic dispatch. When nipple 28 is connected to a suitable source of compressed air and valve 26 opened, the powder will be dispatched to the right in the air screen as a result of the Venturi action within throat 6. The succeeding powder will be fed downwardly both by the action of gravity and by the succession of the air stem induced.

The right-hand end of casing tube 32 is threaded as at 34 into a ground joint 36. While any one of several well known models for ground joint 36 may be embodied it is important that the exterior member thereof be turnable with respect to casing pipe 32 and, when the exterior member is turned, that hollow spike 4 should turn with it. In the embodiment illustrated ground joint 36 comprises an internally threaded 35 member 38 engaged over the threads 34 of casing tube 32, member 38 having on its end a flange 40 fitting in an L-shaped seat 42 of a nut headed internally member 44, an internally extended flange 46 may be welded or otherwise secure to the end of nut 44 for cooperation with flange 40 40 for holding the parts in rotatable but substantially air-tight relationship.

On the right hand side of ground joint 36 there is threadably engaged hollow spike 4 preferably 50 formed of an elongated hollow pipe 48 having its end wall cut away as a half moon as indicated at 50. The pointed spike end of hollow spike 4 is formed from a solid bar tapered to a point 52 and having a recess 54 cut therein. The pointed spike end is welded to the end of pipe 48 with the left hand end of recess 54 registering with the

hollow of pipe 48. The bottom of the recess curves upwardly as indicated at 56 so as to provide a smoothly curving surface.

In operation the hollow spike 4 is inserted by jabbing its pointed end 52 into the bed of coals whereupon manual valve 26 is opened and chemical from hopper 8 is dispatched into the bed of coals from opening 54.

It is apparent from the formation of recess 54 that the device is self cleaning in that neither the chemical powders nor the burning coals are liable to become lodged in the opening and, in event they do, they will be driven out by the air blast and entrained chemical powders. In order to treat the entire bed of coals adjacent the point at which the hollow spike end is inserted, the operator grasps the enlarged nut 44 of ground joint 36 and rotates it with respect to throat 6 so that the chemical powder is uniformly driven through the 360° in the bed of coals. By this mechanism there is no danger of spilling the contents of hopper 8 which also is maintained in an upright position for assisting the gravity feed of the chemical powders to the throat section 6.

If the chemical forms a crust inside of the pipe and point after a period of time, the gun should be placed in a vertical position resting on the spike point and tapped lightly to remove the crust.

The invention entailed above is not limited to the specific elements shown but is intended to cover all modifications and analysis within the scope of the following claims.

I. claim:

1. A spray injector for feeding powdery materials into the fuel bed of furnaces comprising in combination, an elongate hollow open-ended tubular casing having front and rear ends, an input tube on the rear end of said casing adapted for connection to a source of compressed fluid, said casing having an opening through the side wall thereof located adjacent said rear end, a hopper having an opening in the bottom thereof, a hollow coupling member supporting said hopper on said casing and connecting the opening in the bottom of the hopper with the opening in the side wall of said casing whereby, when said casing is held substantially horizontally with said hopper upright, gravity assists material in said hopper to

feed downwardly into said casing, a relatively small open-ended hollow tube coaxially disposed in said casing with its rear end fitting in said input tube and in fluid-tight connection therewith, a hollow spike tube extending forwardly from said casing, said spike tube having a solid spike point on its front end and a relatively large elongate outlet opening in one side only thereof extending rearwardly from said joint, and a rotatable, substantially air-tight fitting joining the rear end of said spike tube and the front end of said casing whereby said spike tube may be rotated to inject material from said hopper in various directions while said hopper is maintained substantially upright, said relatively small tube extending across the location of the opening in the side wall of said casing and for a substantial distance forwardly therefrom whereby to deter blow-back into said hopper when said outlet opening is blocked.

2. The combination claimed in claim 1, said casing being diametrically enlarged in the location of the opening in the side wall thereof and relatively reduced between said location and the front end thereof, whereby to provide a temporary repository for the material fed downwardly from said hopper and whereby to define a relatively reduced throat between the inner wall thereof and said relatively small tube.
